UNITED STATES PATENT OFFICE.

RUFUS G. FORDYCE, OF CHICAGO, ILLINOIS.

MACHINE FOR DEPOSITION OF COATING.

Application filed August 17, 1926. Serial No. 129,775.

This invention relates to machines for deposition of liquid coating on surfaces in the form of letters, numerals, other characters, ornamental configurations, etc., under the influence of a current of air.

It is an object of the invention to provide a machine that deposits predetermined requisite quantities of coating on an area of stock, the coating being conveyed periodical-
ly from its source by controlled air currents to the places of deposit and excess coating being conveyed or returned to the source.

Another object of the invention is to provide means under control of air pressure and suction for feeding coating to air currents conveying the latter to places of deposition.

When considered with the description herein, the characteristics of the invention are apparent from the accompanying drawings, forming part hereof, wherein there is disclosed, for purposes of illustration, an adaptation of the invention to a hand-controlled machine for deposition of luminous compound in the shape of numerals on a strip of stock from which dials of time-pieces subsequently are to be severed.

Although the disclosures herein are exemplifications of what are considered preferable adaptations to a machine of that kind, it is to be understood that it is not the intention to be limited necessarily thereto in interpretation of the claims, as modifications in the disclosed machine and adaptations in other respects, within the limits of the claims, can be made without departing from the nature of the invention.

Like reference-characters refer to corresponding parts in the views of the drawings, of which—

Fig. 1 is a perspective view;
Fig. 2 is a section on the line 2—2, Fig. 1;
Fig. 3 is a fragmentary perspective, the upper plate of the raceway being shown in section taken on the line 3—3, Fig. 1, the stencil being broken away, and the table being shown in depressed position;

Fig. 4 is a view of an alternative form of machine;

Fig. 5 is a section of the control-valve.

Tanks and associated parts.

Referring to Figs. 1, 2, and 3, the machine includes two oppositely-disposed spaced-apart aligned fluid-tight tanks 6 and 7, for

containing coating composition, arranged to rest on any suitable base (not shown).

The tank-walls at their tops have outwardly-flaring flanges 8 for accommodation of bolts or other suitable fasteners 9, which hold covers 10 in fluid-tight association therewith. Lugs 11 on the tanks extend under the space therebetween.

The facing walls of the two tanks have oppositely-positioned outwardly-extending flanges 12. Above them these tank-walls are formed with elongated substantially horizontal mouths 13, which lead into a raceway connecting the tanks, and which widen toward the interior of the tanks. The upper wall of the raceway is a plate 14, which may be formed integrally with the facing tank-walls, as shown.

Stencil-plate.

The lower wall of the raceway is afforded by a stencil-plate 15, spaced from and below the plate 14. The stencil-plate is secured to side reinforcing members 16, which rest on the flanges 12, and it rests also on end members 17, which are secured to the upper wall 14 of the raceway by fastenings 18. The stencil-plate is held in this manner in such position that its upper surface is in substantially the same plane as the lower sides of the mouths 13. On removing the fastenings 18 and end members 17, the stencil may be withdrawn by sliding on the flanges 12, when another plate may be substituted.

The stencil has extending therethrough openings 19 of the shape and disposition of the characters or other configurations it is desired to form on stock treated by the machine. For the present exemplification of the invention, those openings may be of the shape of numerals arcuately arranged in the relative positions it is desired such characters shall appear on stock from which dials of timepieces subsequently are severed.

In the case of certain characters—as, for example, "4", "6", "8", "9", "0"—the central parts thereof, which are detached from the main body of the stencil, are supported by hollow tubes 20, which extend through those parts, and which extend also upwardly through, and are secured in, the upper wall 14 of the raceway. The upper ends of these tubes are covered by flexible caps 21 of suit-

able fluid-tight elastic material, such as rubber, for a purpose hereinafter explained.

Stock-holding table.

5 A vertically-movable table 22 below the stencil has depending members 23 fixed thereto, which extend through and are guided by the lugs 11. Springs 24 interposed between the table and lugs press the former upwardly to hold a strip of stock A, from which dials of timepieces subsequently are to be severed, tightly against the under side of the stencil. The stock is positioned properly on the table by one or more upwardly-extending pins 25 thereon, which protrude into one or more holes B in the stock. The table is depressed from the stencil by a link 26 connected thereto and to a lever 27, so that a piece of stock may be placed on the table and withdrawn therefrom after stenciling.

Coating-feeders.

25 Substantially vertical guide members 28 are secured in oppositely-disposed pairs inside of each tank to end walls thereof adjacent to the mouth 13. A slide 29 of a coating-feeder protrudes into the space between each pair of guides, and each pair of slides is secured to, or is an integral part of, depending legs 30 of a cross-strap 31. An arcuate scoop 32 is secured to and between the legs 30, and its lower edge is positioned to move vertically close to, or in contact with, the side wall of the tank across the mouth.

40 A rod 33 connected to the strap 31 extends upwardly through the cover of the tank and through a threaded nipple 34 of the cover, and it is connected to a piston 35 having an upwardly-extending pin 36 thereon. The piston is reciprocable in a casing 37, preferably cylindrical, which is screwed at its lower end onto the nipple. An orifice 38 in the head of the opening normally is closed by an outwardly-openable valve 39. The valve has an inwardly-extending stem 40 in the path of movement of the pin 36 of the piston, and it is held normally in closed position by a spring 41 interposed between the head and an abutment 42 of the stem. The pin 36 is arranged, on upward movement of the piston, to contact with the lower end of the stem and lift the valve from its seat. A spring 43 in the casing, interposed between the head and piston, tends to press the latter downwardly against the lower end of the casing and to maintain the coating-feeder emersed in coating in the tank.

60 *Air ducts and valve.*

65 A pipe 44 is in communication with a vacuum-tank or other device for maintaining fluid pressure below atmospheric and with a chamber within a valve-casing 45.

Two ports 46 are in communication with the chamber. Valves 47, controlled by cams 48 on a shaft 49, are arranged to open either port at a time and to permit both to remain closed.

70 A pipe 50 is in communication with one of the ports and the interior of the tank 6 through the cover 10 and with the interior of the piston-casing of the tank 7 by means of a pipe 51. A pipe 52 is in communication with the other port and the interior of tank 7 through the cover thereof and with the piston-casing of tank 6 by means of a pipe 53.

75 *Operation.*

80 Liquid coating material is charged into the tanks to a level below the raceway-mouths, and by recharging from time to time it is kept at an amount requisite for sufficient emersion of the feeders.

85 Coating is caused to pass under the influence of air currents moving through the raceway or passage from one tank onto the stencil and into the configuration-openings thereof and onto the stock, and the excess coating into the other tank, the air currents, flowing successively in opposite directions from one tank to the other.

90 Assuming that the feeders are in the positions shown by Fig. 2, a current of air carrying coating onto the stencil just has moved from tank 6 to tank 7 as a result of exhaustion of air from tank 7 through the pipe 52. By the time the exhaust action in tank 7 and flow of air through the raceway ceases, either by closing of the valve controlling the pipe 52 or upon diminishment of pressure in the tanks to that of the vacuum-tank or its equivalent, the pin 36 of the piston will have lifted the valve 39 of tank 6 and relieved the piston of suction action through pipe 53, and permitted the feeder in tank 6 to be returned by the spring 43 from the upper position shown to its lower position in the coating in the tank.

95 Upon lowering the table, the strip of stock that has been treated may be withdrawn and another substituted therefor, or in the case of a strip longer than the width of the stencil it may be moved to bring another and untreated area under the stencil, and the table then is permitted to press the stock against the bottom of the stencil.

100 Thereupon, the valve is operated to open port 46 with which pipe 50 is in communication, and this will result in exhaust of air from tank 6 and the piston-casing of tank 7, movement of a current of air exhausted from tank 7 through the raceway into tank 6, 115 movement of the feeder of tank 7 upwardly across its mouth and deposit coating in the latter, and the carrying of coating by the air current across the stencil, whence some of it will flow through the openings thereof onto 120

the stock and the excess will be carried into tank 6. Upon cessation of flow of air through the raceway, the feeder in tank 7 will be returned to immersion in the coating 5 in the bottom thereof in the same manner as described for that of tank 6.

When the table is pressed upwardly to bring the stock against the bottom of the stencil, some of the air therebetween will be 10 forced upwardly through the openings of the stencil and some will enter the tubes 20 and expand the caps 21. When the table is retracted from the stencil to release the stock, the tubes and their caps will furnish air between the stock and stencil and prevent retention of the stock against the stencil under the influence of suction.

The stenciling operation thus described may be repeated indefinitely and alternately 20 from each tank to the other. The amount of coating in each tank will remain substantially the same as that in the other, for the excess not deposited on the stock is carried alternately into each tank.

25 It is to be observed that, within the limitations of practicability of handling lengths of stock and other factors pertaining to the functioning of such machines, the tanks, raceway, stencil, and table may be made sufficiently long for the simultaneous stenciling of comparatively extensive areas of the surface of stock. Thus, in the deposition of coating in the form of numerals and other configurations on stock from which time-piece-dials subsequently are to be formed, 30 one stencil may have a plurality of sets of configuration-forming openings, with the result that a plurality of dial areas may be stenciled at the same time.

40 *Alternative form.*

An adaptation of the invention to a single-tank machine is exemplified by Fig. 4. In 45 this form, the plate 14 constitutes the bottom wall of a raceway or chamber, and it is at an inclination to the horizontal and slopes downwardly to the mouth of the tank. The stencil-plate is in substantially horizontal disposition, and it constitutes the upper wall of the raceway or chamber. The plate and stencil are closed together at the opposite ends and at the sides.

50 A pipe 50^a is in communication with the vacuum-tank or other device for maintaining fluid pressure below atmospheric and with the interior of the tank and with a piston-casing of a feeder like that shown in the double-tank machine. The pipe is controlled by a valve 50^b arranged to open and close its communication with the vacuum-tank or the like. A pipe 54, controlled by a valve 55, is in communication with the interior of the tank and with the atmosphere or with an air-pressure device.

When the valve is operated to open the pipe to the vacuum-tank or the like, air is exhausted from the coating-tank and from the space between the plate 14 and the stencil, it being assumed that stock is held tightly, in 50 any suitable manner, against the top of the stencil at that time, and the feeder is moved upwardly across the mouth to deliver coating in sufficient quantity thereto. Then the valve 50^b is operated to shut off communication with the vacuum-tank or the like, and the valve 55 is operated to permit air to rush into the tank. Thereupon, air will fill the tank to atmospheric pressure or above and at 55 the same time rush into the closed space below the stencil and carry into the stencil openings coating that has been delivered to the mouth. The feeder, upon release of suction in its control-casing, will return to position below the mouth. Excess coating not 60 taken up by the stock will be drawn by suction out of the stencil openings, and it will flow by gravity, and also to some extent under the influence of suction, back to the coating-tank.

65 What I claim as new, and desire to secure by Letters Patent, is—

1. In a stenciling-machine, a coating-container, a raceway communicating therewith, a stencil at a side of said raceway, a stock-holding member at the outside of said stencil, and means whereby air is moved from 70 said container into said raceway.

2. In a stenciling-machine, a coating-container, a raceway having a mouth leading 75 from said container, a coating-feeder movable adjacent to said mouth, a stencil at a side of said raceway, a stock-holding member at the outside of said stencil, and means whereby air is moved from 80 said container into said raceway.

3. In a stenciling-machine, a coating-container, a raceway communicating therewith, a stencil at a side of said raceway, a stock-holding member at the outside of said stencil, and means whereby air is exhausted 85 from and released into said container.

4. In a stenciling-machine, a coating-container, a raceway having a mouth leading 90 from said container, a coating-feeder movable adjacent to said mouth, a pneumatic operating device for said feeder, a stencil at a side of said raceway, a stock-holding member at the outside of said stencil, an exhaust-pipe connected with said container and 95 a pneumatic device, and a control-valve for 100 said pipe.

5. In a stenciling-machine, a stencil, a stock-holding member at one side thereof, and means whereby air containing coating is 105 passed across the other side of said stencil.

6. In a stenciling-machine, two coating-containers, a raceway between and in communication with said containers, a stencil at a side of said raceway, and means whereby 110

air is caused to pass from one of said containers to the other through said raceway.

7. In a stenciling-machine, two coating-containers, a raceway between and in communication with said containers, a stencil at a side of said raceway, and means whereby currents of air are caused to pass alternately from each of said containers to the other through said raceway.

10. 8. In a stenciling-machine, two coating-containers, a raceway between and in communication with said containers, a stencil at a side of said raceway, and means whereby air is exhausted intermittently from one of said containers.

9. In a stenciling-machine, two coating-containers, a raceway between and in communication with said containers, a stencil at a side of said raceway, and means whereby air is exhausted alternately from each of said containers.

10. In a stenciling-machine, two coating-containers, a raceway having mouths leading from said containers, a coating-feeder movable adjacent to each of said mouths, a stencil at a side of said raceway, and means whereby currents of air are caused to pass alternately from each of said containers to the other through said raceway.

30. 11. In a stenciling-machine, two coating-containers, a raceway having mouths leading from said containers, a coating-feeder movable adjacent to each of said mouths, a pneumatic operating device for each of said feeders, a stencil at a side of said raceway, and controllable air-exhaust means connected with said containers and pneumatic devices.

12. In a stenciling-machine, two coating-containers, a raceway having mouths leading from said containers, a coating-feeder in each of said containers movable adjacent to its mouth, a pneumatic operating device for each of said feeders, a stencil at a side of said raceway, for each container an exhaust-pipe connected therewith and with the feeder-operating device of the other, and control means for said pipes.

13. A stenciling machine comprising two oppositely-disposed fluid-tight coating-containers, a plate connected to facing walls of said containers constituting the upper wall of a raceway extending between said containers, a stencil-plate at the bottom of said raceway, and means whereby air is caused to pass from each of said containers to the other through said raceway.

14. In a stenciling-machine, a coating-container, a plate constituting a wall of an air-passage in communication with said contain-

er, a stencil at the opposite side of said passage, and air-ducts in said plate extending through said stencil.

15. In a stenciling-machine, a coating-container, a plate constituting a wall of an air-passage in communication with said container, and a stencil constituting an opposite wall part of said passage.

16. In a stenciling-machine, a coating-container, a plate constituting a wall of an air-passage in communication with said container, a stencil constituting an opposite wall part of said passage, and air-ducts in said plate extending through said stencil.

17. In a stenciling-machine, a coating-container, a plate constituting a wall of an air-passage in communication with said container, a stencil at the opposite side of said passage, air-ducts extending from the opposite side of said plate through said stencil, and expansible caps on the outer ends of said ducts.

18. In a stenciling-machine, a coating-container, a plate constituting a wall of an air-passage in communication with said container, a stencil at the opposite side of said passage having configuration-forming openings, and supporting members for parts of said stencil within said openings carried by said plate.

19. In a stenciling-machine, two oppositely disposed coating-containers, a plate connected to facing walls of said containers, a stencil below said plate, there being an air-passage between said plate and stencil in communication with said containers, and members secured to said plate closing the sides of said passage.

20. In a stenciling-machine, a coating-container having a mouth and an air-passage communicating therewith, a stencil at a side of said passage, a coating-feeder movable across said mouth, a casing, a piston therein connected with said feeder, and a valve-controlled air-pipe in communication with said casing.

21. In a stenciling-machine, a coating-container having a mouth and an air-passage communicating therewith, a stencil at a side of said passage, a coating-feeder movable across said mouth, a casing having an air-inlet, a valve normally closing said inlet, a piston in said casing connected with said feeder arranged to open said valve, and a valve-controlled air-pipe in communication with said casing.

In testimony whereof I affix my signature.

RUFUS G. FORDYCE.
